DEVICE FOR CONTROLLING TENSION IN SHEET MATERIAL

Application filed May 29, 1929. Serial No. 366,848.

This invention relates to devices for controlling tension in sheet material, and more particularly to devices capable of being applied to rolls containing sheet material, such as paper.

A general object of this invention is to provide a device which will overcome the objections and defects of prior devices.

A further object of the invention is to provide a tension controlling device which is readily and quickly detachable from a shaft and which is capable of easy and quick application to a shaft.

The invention also contemplates the provision of a device which is simple in construction, which is easy to use and which is adjustable.

A further feature of the invention is to provide a device of the character set forth which is unitary in character and which is practically self contained.

Other objects and features of the invention will become apparent from the following description taken in conjunction with the accompanying drawings, in which:

Fig. 1 illustrates a front elevation of a paper roll which has my improved device attached thereto;

Fig. 2 is a side elevation of Fig. 1;

Fig. 3 depicts a side view of my improved device, partly in the section for the purpose of clarity;

Fig. 4 is a sectional view taken on the line 4-4 of Fig. 3;

Fig. 5 is a similar view of Fig. 3 with a control lever just about to come into action;

Fig. 6 is a sectional view taken on the line 6-6 of Fig. 3, with the central shaft in full to illustrate a bayonet joint;

Fig. 7 shows a bottom plan view of the device depicted in Fig. 3; and

Figs. 8 and 9 are diagrammatic views to be used in the explanation of the operation of my improved device.

Although my improved device for automatically controlling the tension in sheet material as it leaves the roll is applicable to many industries which will be described herein with particular reference to the paper industry. It is to be noted, however, that my

invention is not limited to the paper industry, but only by the scope of the pending claims.

Referring more particularly to Figs. 1 and 2, the numeral 1 designates brackets which support a shaft 2 in the usual manner. 55 Mounted upon the shaft 2 is a roll 3 of paper which is maintained in proper alignment with respect to the shaft by use of the usual adjusting cones 4. On the right end of the shaft my improved device is mounted in any suitable manner. This device consists essentially of a central drum 5 about which are clamped jaws 6, 6 which are secured together or hinged at their upper end by means of a special hinge bolt 7 and at their lower end by a slide member 8. Associated with slide member 8 is a 60 prying arm 9 which opens the jaws 6, 6. 65

The prying arm 9 projects downwardly from slide member 8 and is adapted to engage a stop bolt 10 extending from the right end bracket 1. The function of the prying or reaction arm is to pry jaws 6, 6 apart when the shaft 2 is rotated. The greatest prying effect of arm 9 and the least clamping effect of jaws 6, 6 occur when the roll 3 of sheet 70 material has the largest diameter and the least prying effect and the greatest clamping effect occur when the roll 3 has the smallest diameter. The relation of the size of the roll to the prying effect is of particular importance due to the fact that when the roll is largest the speed of rotation is slowest and the clamping effect of the jaws on the drum is more effective at the slow speed whereas when the roll becomes smaller the speed of 75 rotation becomes greater and the clamping effect of the jaws on the drum is not as effective at slower speeds of rotation. This means that at slow speeds of rotation when the roll is large the prying effect must be 80 greatest in order to open the jaws and to decrease the over-all clamping on the drum and that at high speeds of rotation when the roll is small the prying effect must be least in order to permit the jaws to close tightly on the drum and to increase the over-all clamping on the drum. 85

The detailed construction of my device will be readily seen from Figs. 3 to 7. In these figures the jaws 6 are shown as cast metal 100

members having side projecting ribs 11 and an inner transverse web 12. At the top of each jaw an appropriate lug 7' is provided for the reception of bolt 7. A slot 13 is provided near the lower end of each member through which slide 8 may pass. This slide is held in position by means of pins 14 cooperating with compression springs 15 which are seated within the slide member and which are held in place by set screws 16. At the center of the slide member, a prying or reaction bar 9 is pivoted by means of pin 17. Prying bar 9 is adapted to push the slide member 8 via pin 17 either to the left or to the right depending upon the direction of rotation of roll 3. In the drawings (see Fig. 5) the slide member is shown as being moved by bar 9 to the right. When this movement occurs roll 18, which is mounted directly below pin 17 on bar 9, engages a hard face plate 19 which is secured to the inner end of the bottom of jaw 6. Face plate 19 may be secured to jaw 6 by any appropriate means such as set screws 20.

On the inner face of each jaw web 12 I provide a frictional pad or surface 21, such as well known asbestos friction lining. This lining is held in place by set screws 22 or the like and is held in engagement with the outer periphery of central drum 5. This drum is secured to shaft 2 by means of a bayonet pin 22 projecting therefrom and fitting in slot 23 in the shaft. The bayonet slot 23 is provided at its innermost end with a transverse slot 24 adapted to engage bayonet pin 23 in either direction of rotation of the drum and shaft. Central drum 5 is preferably made with a plurality of ventilating apertures 25 which tend to cool the drum when in operation. This ventilation, of course, tends to keep the temperature of the frictional elements relatively low, and thus, prevents them from burning out.

After my device has been used for awhile the frictional lining wears away so that an appropriate adjustment must be made to maintain the proper friction on the central drum. This adjustment is effected by turning locknuts 26 on the ends of bolt 7 over pivot plates 27 so as to bring the two jaws 6-6 closer together and, thus, reestablish the proper frictional contact between lining 21 and central drum 5. It should be noted, however, that this adjustment ordinarily does not have to be made very frequently.

Jaws 6 are held in place by means of a pair of annular plates 27' fastened to each side of central drum 5. Between the outer face of central drum 5 and the inner face of plates 27' 27 wood-oilless washers 28 which are interposed to minimize the friction between the moving plates 27 and the outer faces 29 of stationary jaws 6. These wood-oilless washers, as is well known, provide excellent lubrication for the parts with which they are in

contact without the necessity of receiving any extraneous lubricating agent. In practice I have found that the wood-oilless washers may be used for long periods of time before renewing them. This feature is of particular importance in the present instance because if an extraneous lubricating agent were required it would ultimately seep through the various parts and ultimately get into contact with the peripheral face of central drum 5 and contact in faces of lining members 21 with a consequence that the friction between the lining and the drum would be reduced to a negligible amount.

The operation of my improved tension controlling device is simple and will be readily apparent to those skilled in the art. Shaft 2 supporting a roll of paper 3 is positioned on brackets 1 in such a manner that the right hand end of the shaft projects beyond bearing 30 of the right hand bracket. The right hand end of the projecting shaft is provided with bayonet slot 22 as described before so that my device may readily and quickly be mounted on the shaft by sliding bayonet pin 22 in bayonet slot 23 and the internal bore 31 of central drum 5 on shaft 2. Stop bar 10 is then adjusted so that when the reaction bar 9 contacts with bar 10, it will be engaged between a pair of collars 32. Set screws 16 are adjusted to put springs 15 under the proper compression and thus clamp jaws 6 with their frictional lining 21 in contact with central drum 5 with a suitable friction. The paper is drawn from the upper side of the roll by suitable mechanism (not shown) and the roll 3 is set in rotation. In the present case the rotation is illustrated as being counter clockwise. As the roll 3 and shaft 2 rotate, central drum 5 is rotated therewith because of the bayonet joint. The rotation of central drum 5 causes a frictional grip on lining 21 and thereby gives the tension control device a tendency to rotate as a whole unit. As the device rotates reaction bar 9 comes into contact with stop bar 10 which prevents any further rotation of the clamping jaws and associated parts. This causes a certain frictional drag on the shaft so as to put the web of paper leaving the roll under a certain tension. By the proper initial adjustment of springs 15 any desired or predetermined tension may be established in the sheet material.

In Fig. 8 the roll is depicted as being approximately full size so that there is a leverage arm between the center of the shaft and the periphery of the roll of say about three feet. This relatively large leverage arm causes a corresponding large reaction pressure on reaction bar 9 which is in engagement with stop bar 10. The reaction bar being subject to this relatively large reaction pressure tends, via slide member 8, to pry apart the clamping jaws 6 against the pressure of compression springs 15 and, thus, decrease the

friction existing between lining 21 and the periphery face of central drum 5 so that there is only a relatively small frictional drag existing at the start of the operation or run. It should be noted that the over-all effect of springs 15 is not affected by movement of slide member 8 because as one spring becomes shorter the second becomes larger, and, thus, compensates for changes in the first spring.

10 In Fig. 9, however, the roll has become very much smaller so that the leverage arm between the center of the shaft and the periphery of the roll is decreased. This causes a corresponding decrease in the reaction pressure on the reaction bar 9 with a corresponding decrease in the prying effect upon the clamping jaws 6. The jaws are thus pressed together by springs 15, 15 in the slide member 8 to a greater degree and consequently bring 20 about an increase of friction between the lining 21 and the peripheral face of central drum 5.

It will be observed that my invention provides a device for automatically controlling 25 a web of sheet material being unwound from a roll and that my improved device is provided with a construction wherein the clamping jaws are not opened by the direct action of the prying bar on a face plate at the end 30 of one of the jaws but by the indirect action of the prying bar on the slide which coacts with one of the pins 14 to effect closing of the clamping jaws. By the utilization of this construction considerable wear of the friction lining on the clamping jaws can occur 35 before adjustment of bolt 7 is necessary. In fact the space or clearance between face plates 19 and the roll 18 on the prying bar can be reduced very materially without affecting the functioning of my device.

It will also be noted that my invention provides a device of the character herein set forth which eliminates slackness in the web of sheet material between the point where it is drawn off the roll and the point where it is used even when the roll slows down and stops because the clamping of the jaws on the drum becomes more effective as the roll rotates slower and the over-all frictional drag keeps in step with the decreasing speed of the roll to preserve a taut condition in the sheet material and to prevent any substantial slackness therein.

Although I have described a specific embodiment of my invention, it is to be understood that the invention is not restricted to such particular embodiment. Various modifications thereof in detail and in the arrangement of the parts may be made by those skilled in the art without departing from the invention as defined in the claims.

I claim:

1. A device for controlling the tension in sheet material leaving a roll of such material which comprises a hollow drum provided

with ventilating apertures, means associated with said drum for securing it to a shaft, a pair of metal jaws surrounding said drum and having internal webs adjacent the periphery of said drum, frictional lining secured to each of said webs for bearing against the periphery of said drum, lugs positioned at one end of said jaws, a hinge bolt operatively associated with said lugs for holding the jaws together at one end, slots provided in said jaws at the other end thereof, a pin secured in each slot, a slide member fitting in said slots and cooperating with said pins, resilient means associated with said slide member for bearing against said pins and 75 clamping the jaws together so as to bring the frictional lining in contact with the peripheral face of the drum, and a prying bar pivotally mounted at the middle of said slide, member between said two jaws and adapted to engage one of the projecting ends of said jaws and to pry the jaws apart against said resilient means whereby the grip of said frictional lining is decreased.

2. A device for controlling the tension in sheet material leaving a roll of such material which comprises a hollow metal drum provided with ventilating apertures, means associated with said drum for securing it to a shaft, a pair of opposed, mating metal jaws 90 surrounding said drum and having internal webs adjacent the periphery of said drum, frictional lining secured to each of said webs for bearing against the periphery of said drum, lugs positioned at one end of said jaws, 95 an adjustable hinge bolt operatively associated with said lugs for holding the jaws together at one end, slots provided in said jaws at the other end thereof, a pin secured in each slot, a slide member fitting in said slots 100 and cooperating with said pins, adjustable resilient means associated with said slide member for bearing against said pins and clamping the jaws together so as to bring the frictional lining in contact with the peripheral face of the drum, and a prying bar pivotally mounted at the middle of said slide member between said two jaws and having a roll which is adapted to engage one of the projecting ends of said jaws and to pry the jaws 105 apart against said resilient means whereby the grip of said frictional lining is decreased.

3. The combination comprising a shaft adapted to carry a roll of sheet material, a pair of brackets supporting said shaft, a stop bolt secured to and projecting from the side of one of said brackets, and a reaction braking device for automatically controlling the tension in the sheet material leaving the aforesaid roll of such sheet material which 120 comprises a drum capable of fitting on a shaft, a pair of hinged clamping jaws surrounding said drum, a slide member connecting the said jaws at their ends opposite to the hinged portion and resiliently clamping the jaws in 125

contact with said drum, and a reaction bar associated with said slide member and adapted to contact with said stop bolt and to pry said jaws apart whereby the clamping contact on said drum is decreased.

4. The combination comprising a shaft adapted to carry a roll of sheet material, a pair of brackets supporting said shaft, a stop bolt secured to and projecting from the side 10 of one of said brackets, and a reaction braking device for automatically controlling the tension in the sheet material leaving the aforesaid roll of such sheet material which comprises a central drum, a bayonet pin projecting 15 from the interior of said drum and adapted to engage a bayonet slot in a shaft carrying a roll of sheet material, a pair of clamping jaws fitted around said drum, a hinge member at one end of said jaws to secure 20 them together, a slide member positioned at the other end of said jaws to hold them in resilient compression, and a reaction bar pivotally mounted on said slide member and adapted to contact with said bolt and to 25 engage an adjacent end of one of said jaws to pry the jaws apart.

5. The combination comprising a shaft adapted to carry a roll of sheet material, a pair of brackets supporting said shaft, a stop bolt secured to and projecting from the side 30 of one of said brackets, and a reaction braking device for automatically controlling the tension in the sheet material leaving the aforesaid roll of such sheet material which comprises a hollow drum provided with ventilating apertures, means associated with said drum for securing it to a shaft, a pair of metal jaws surrounding said drum and having 35 internal webs adjacent the periphery of said drum, frictional lining secured to each of said webs for bearing against the periphery of said drum, lugs positioned at one end of said jaws, a hinge bolt operatively associated with said lugs for holding the 40 jaws together at one end, slots provided in said jaws at the other end thereof, a pin secured in each slot, a slide member fitting in said slots and cooperating with said pins, resilient means associated with said slide 45 member for bearing against said pins and clamping the jaws together so as to bring the frictional lining in contact with the peripheral face of the drum, and a prying bar pivotally mounted at the middle of said slide 50 member between said two jaws and adapted to contact with said bolt and to engage one of the projecting ends of said jaws and to 55 pry the jaws apart against said resilient means whereby the grip of said frictional lining is decreased.

6. The combination comprising a shaft adapted to carry a roll of sheet material, a pair of brackets supporting said shaft, a stop bolt secured to and projecting from the side 60 of one of said brackets, and a reaction braking

device for automatically controlling the tension in the sheet material leaving the aforesaid roll of such sheet material which comprises a hollow metal drum provided with 70 ventilating apertures, means associated with said drum for securing it to a shaft, a pair of opposed, mating metal jaws surrounding said drum and having internal webs adjacent the periphery of said drum, frictional lining secured to each of said webs for bearing against 75 the periphery of said drum, lugs positioned at one end of said jaws, an adjustable hinge bolt operatively associated with said lugs for holding the jaws together at one end, slots provided in said jaws at the other end thereof, a pin secured in each slot, a slide member fitting in said slots and cooperating with said pins, adjustable resilient means associated with said slide member for bearing against 80 said pins and clamping the jaws together so as to bring the frictional lining in contact with the peripheral face of the drum, and a prying bar pivotally mounted at the middle of said slide member between said two jaws and having a roll which is adapted to engage 85 one of the projecting ends of said jaws and to 90 pry the jaws apart against said resilient means when the free end of the bar contacts with and pushes against said stop bolt, whereby by the grip of said frictional lining is decreased.

7. The combination comprising a shaft adapted to carry a roll of sheet material, a pair of brackets supporting said shaft, a stop bolt secured to and projecting from the side 100 of one of said brackets, and a reaction braking device for automatically controlling the tension in the sheet material leaving the aforesaid roll of such sheet material which comprises a drum capable of fitting on a shaft, a pair of hinged clamping jaws surrounding said drum, a slide member connecting the said jaws at their ends opposite to the hinged portion and resiliently clamping the jaws in contact with said drum, a reaction bar associated with said slide member and adapted to contact with said stop bolt and to pry said jaws apart whereby the clamping contact on said drum is decreased, a pair of retaining plates secured to the sides of said jaws to hold them in position around the drum and wooden oilless washers interposed between said retaining plates and the face of contiguous jaws.

8. The combination comprising a shaft adapted to carry a roll of sheet material, a pair of brackets supporting said shaft, a stop bolt secured to and projecting from the side 110 of one of said brackets, and a reaction braking device which comprises a pair of opposed mating jaws resiliently clamped about a drum which is mounted on a projecting end of said shaft and a reaction bar associated with said jaws and adapted to engage the stop bar on 120

the bracket adjacent to the projecting end of the shaft when the shaft and roll thereon is rotated so as to pry the jaws apart with a force which is proportional to the distance between the periphery of the roll of sheet material to the center of the shaft.

5 In testimony whereof, I have hereunto set my hand.

FREDERICK J. LANZ.
